CONTROLS FOR BOILER INSTALLATIONS

Harvey C. Mittendorf, East Orange, N. J., and
 Albert C. Foster, Pittsburgh, Pa., assignors to
 International Combustion Engineering Cor-
 poration, New York, N. Y., a corporation of
 Delaware

Application June 27, 1930, Serial No. 464,132

11 Claims. (Cl. 110—106)

This invention relates to controls for boiler installations and will be described in connection with installations in which the furnace is directly fired from a mill such as a roller mill, i. e., installations in which a feeder receives coal from a bin and delivers it to a pulverizer mill from which it is drawn by an exhauster and delivered into the furnace by means of suitable burners.

In such installations difficulties in firing are encountered because under certain conditions the mill becomes overloaded with coal. Under other conditions there is not sufficient coal in the mill to ensure proper operation. The conditions referred to will be understood from the following.

15 In steam generating installations of the character described it has been found that the mills tend to overload due either to a high percentage of fines being delivered into the mill at any one time, changes in the type of coal, or to a sudden 20 reduction in boiler rating which finds the mill with more coal than is necessary for the reduced rating.

We are aware that automatic combustion controls have been employed in such installations 25 in which the speeds of the various pieces of fuel handling equipment are changed to take care of the new load conditions, but we have found that there is a period in which the mill is overloaded because of the storage of coal in it that 30 took place when the boiler was operating at higher ratings and, therefore, even though the speeds of the devices be reduced at such a time, the overload condition will be further aggravated rather than helped.

35 Stated more fully the known automatic combustion controls do not use the positional idea. By this we mean that they do not take any definite position for any particular steaming rate of the boiler. They simply increase or decrease 40 the speeds of the motors of the various pieces of fuel handling equipment whenever a change in pressure in the steam header line occurs. Consequently when the steaming rate changes the slight change in header pressure causes the controls to be moved to a new position which will 45 again give the present header pressure. While the motion of the control may be practically instantaneous it does not necessarily follow that the equipment can immediately adapt itself to 50 the new conditions. Such a case occurs when the steam demand is reduced over a wide range in a very short interval of time. The exhauster, pulverizer and feeder motors will be brought down to their slower speed positions, but, due 55 to the storage of coal in the mill occurring at

such time, the mill becomes partly plugged and although the coal feed rate may be quite low, even this amount of coal feed tends to aggravate the plugging condition. The plugging action within the mill is reflected at the exhauster by 60 an increase suction due to the reduced air flow and the dropping of part of the coal which was in suspension back into the mill. At such times it is desirable to give the mill an opportunity to clear itself before any additional coal is added. 65 From the above it will be seen that the suction at the exhauster is an indication of conditions occurring in the mill and we propose to utilize this suction to overcome difficulties herein fully 70 pointed out.

For example, let us assume that the boiler is operating at a maximum rating and that the feeder, mill, and exhauster are running at their maximum speeds. Under this condition the feeder is supplying coal rapidly to the mill so that 75 a considerable storage of coal takes place in the mill, which is desirable in order to prevent the mill from pounding at its high speed. Since the mill and exhauster, however, are being driven at their maximum speeds proper introduction of 80 fuel into the furnace takes place. Let us assume that the boiler rating is now suddenly reduced to the point where the feeder, mill and exhauster are brought to their slowest speeds by the combustion control mechanism. The air flow which 85 is governed by the exhauster speed then drops off promptly and much of the fines which are in suspension drop back into the mill. Since the mill speed is also greatly reduced the plows of the mill will not throw up the coal sufficiently 90 to be picked up by the air for delivery to the exhauster and burner. It will be seen, therefore, that under the above conditions, coal stores up in the mill, and as the feeder is still delivering 95 coal to the mill, although at reduced speed, still more coal enters the mill to bring about an over-load condition.

One of the primary objects of our invention is to overcome the above difficulties.

Under other conditions of operation there is 100 a period in which insufficient coal is in the mill so that rumbling of the mill takes place. For example, with a sudden increase in the load taken from the boiler, the mill, exhauster, and feeder will be speeded up by the combustion control 105 mechanism so that there would not be sufficient coal in the mill to prevent a sudden decrease in the suction drop through the mill, and while the control mechanism would eventually speed the feeder to the point where a proper level of coal 110

would exist in the mill, there nevertheless is a period in which the supply would be inadequate to prevent rumbling.

We propose, therefore, to provide a system of control whereby such rumbling is prevented.

We also contemplate the provision of a control system adapted to improve the control of boiler installations under conditions when there is a substantial drop of boiler rating from say 10 300% to 200% of rating.

Generally stated, therefore, it is an object of our invention to provide simple and effective control means for installations of the character described whereby proper coal conditions are ensured in the mill when changes in boiler rating take place.

A more specific object resides in the provision of effective mill feeder control in boiler installations.

20 A further object resides in the provision of simple and effective control means in apparatus of the class described whereby approximately constant or predetermined condition of suction may be maintained at the exhauster under different operating conditions.

25 How the foregoing, together with such other objects and advantages as may hereinafter appear, or are incident to our invention, are realized, is illustrated in preferred form in the accompanying drawings, wherein—

30 Fig. 1 is an elevational view of a boiler installation embodying our invention; Fig. 2 is an enlarged elevational view of rheostat operating mechanism which we employ; Fig. 3 is an end view of Fig. 2, and Fig. 4 illustrates a simple form of wiring diagram.

35 The installation illustrated comprises in general a boiler A of any well known type, a pulverized coal burning furnace B having suitable burner means C for the introduction of the fuel, a pulverizer mill D, to which coal is delivered by a feeder device E, a bin F for supplying coal to the feeder device, and an exhaust fan or exhauster G for drawing pulverized coal from the mill D for delivery into the furnace through the medium of the burner means C. A conduit 5 connects the mill to the suction side of the exhauster and a conduit 6 connects the discharge side of the exhauster to the burner C. Electric motors 7, 8 and 9 are employed for driving the feeder E, the mill D and the exhauster G respectively.

40 Control mechanism indicated as a whole by the reference letter H is provided for automatically controlling the feeder, mill, and exhauster motors. In general the control mechanism comprises three automatically operated rheostats 10, 11 and 12, one for each motor, the rheostat 10 being for the feeder motor 7, rheostat 11 for the mill motor 8 and rheostat 12 for the exhauster motor 9, and steam pressure actuated mechanism J for causing the automatic operation of the rheostats.

45 A cam shaft 13 (see Figs. 2 and 3) carrying three cams 14, 15 and 16 is provided and the cams operate levers 17, 18 and 19 pivoted on a support 20. The lever 17 is actuated by the cam 14 and its movement is transmitted to the feeder rheostat 10 by means of a flexible chain or cable 21 which is secured at one end to the free end 22 of the lever 17 and carries a counterweight 23 at its other end. The flexible chain 21 passes around a sprocket wheel 24 secured on the rheostat shaft 25 and then over an idler sprocket 26 from which the counterweight depends. Thus it will be seen that when the lever moves up and down the

sprocket wheel 24 and rheostat 10 are correspondingly turned.

50 In order to initially set the rheostat or to correct its setting to a preselected position, we have provided a hand operated setting or correcting device 27 adapted to operate on the chain 21, which device comprises a member 28 secured on a rotatable shaft 29 having an operating handle 30, and a pair of sprockets 31, 31, rotatably carried by the member 28, between which the chain passes. When the handle 30 is rotated the run of chain between the lever 17 and sprocket wheel 24 is lengthened or shortened according to the direction in which the member 28 is rotated and this, in turn, rotates the sprocket 24 and rheostat 10 either in a clockwise or counter-clockwise direction to afford setting of the rheostat as desired. The device 27 may be locked in its adjusted position in any suitable manner.

55 Similar mechanisms indicated at 32 and 33 are employed for actuating the mill and exhauster rheostats 11 and 12 respectively, through operation of the levers 18 and 19 associated with the cams 15 and 16. Hand operated setting or correcting devices 34 and 35 are also provided in the mechanisms 32 and 33.

60 The cam shaft 13 is actuated by means of a well known combustion control device indicated at J which is of the type receiving steam for its operation from the boiler. In general the de-

65 vice includes a pressure actuated piston 37 which is subjected to pressure under control of a valve device 38 operated by boiler steam pressure sup-

70 plied thereto by a line 39 leading from a steam header 40 of the boiler. When the steam pres-

75 sure in the line 39 increases, the piston 37 moves

80 upwardly and this movement is transmitted to the cam shaft 13 by means of a link 41 connected at

85 one end to the piston rod 42 and at its other end to a lever 43 secured to the cam shaft. The cam

90 shaft is thus rotated in a direction to cause the

95 cams 14, 15, and 16 to rock the levers 17, 18 and

100 19 upwardly and this in turn operates the rheo-

105 stats in a manner to slow down the motors of the

110 feeder, the mill, and the exhauster. When the

115 steam pressure drops the reverse operation takes

120 place and the motors are speeded up.

125 From the foregoing it will be seen that auto-

130 matic control is provided whereby the motors of

the various pieces of equipment are slowed down

135 when there is an increase in steam pressure and

140 speeded up when there is a steam pressure drop.

Under conditions of gradual decreases and in-

145 creases in steam pressure the above system of

150 control is quite satisfactory for controlling the

155 firing of the furnace to suit changes in load and

160 boiler rating. However, there are conditions in

165 many installations where the changes are sudden

170 and rapid which are not effectively taken care

175 of. This is particularly true in a steel plant

180 where changes in rating are very rapid so that

185 difficulties are encountered in firing due to con-

190 ditions in the mill, as has been pointed out above.

195 In order to overcome such difficulties we sup-

200 plement the above control device by suction op-

205 erated devices adapted to additionally control

210 the mill feeder as will now appear.

215 A pipe connection 44 is taken off the exhauster

220 inlet elbow 45 or at some other convenient point

225 in the mill where there is a maximum amount of

230 suction, and is led to a well known type of suc-

235 tion relay device 46 having a pivoted lever 47

238 adapted to be rocked through the action of the

240 suction on the relay. The pivoted lever 47 is con-

245 nected, by means of a link 48, to any well known

250 150

- form of mercoid switch 49 or other type of switch adapted to make or break the feeder motor circuit. As will be clear from the wiring diagram illustrated in Fig. 4, the mercoid switch 49 is connected into the feeder motor circuit, and, therefore, serves as a controlling medium to start or stop the feeder motor 7, the speed of which is automatically regulated under normal conditions as hereinbefore described.
- 10 Referring to the wiring diagram the circuit for the exhauster motor 9 is shown with the connections such that the motor is operating. Any suitable form of starting switch 50 may be employed. The rheostat 12 is shown in a position in which the motor field is weakened approximately two-thirds.
- 15 The circuit for the pulverizer motor 8 is similar to that just described and includes a suitable form of starting switch 51, the rheostat 11 being shown in position to weaken the motor field approximately two-thirds.
- 20 The circuit for the feeder motor 7 is shown with the connections such that the motor is operating with its field weakened approximately two-thirds by the rheostat 10. The automatic operation of the rheostats 10, 11 and 12 has been described hereinbefore.
- 25 The feeder motor 7 is remotely controlled by a suitable start stop switch 52 when the stop suction relay 46 is in the position corresponding to suction insufficient to cause it to open the control circuit through the medium of the mercoid switch 49. However, when the suction in the relay 46 reaches a predetermined value, the suction relay 30 operates to rock the mercoid switch in a direction to open the mercury contact at 53 so that the circuit to a magnetic switch 54 is interrupted, thus causing the switch to open. This opens the feeder motor control circuit and stops the feeder 35 motor until the mill has cleared itself and the suction at the inlet side of the exhauster has been again restored to its normal value. It is to be noted that with the parts in the position shown in the wiring diagram, the operation of the 40 feeder motor 7 is similar to that of the motors 8 and 9 above described.
- 45 Assuming now that the boiler is operating at high rating with the feeder, mill and exhauster 50 running at their maximum speeds and that the boiler rating is suddenly reduced to the point where the motor rheostats 10, 11 and 12 immediately slow the motors to their slowest speeds, then the suction relay 46 is operated on by high 55 suction due to causes fully pointed out above and the pivoted lever 47 is moved in a direction to open the feeder motor circuit, with the result that the feed to the mill is interrupted for a time and for such a length of time as it takes for the mill to be cleared of sufficient coal to cause a 60 reduction of the suction to normal value. When this occurs the suction relay automatically is reset and the feeder motor circuit is closed to again start the feeder in operation which will then be under control of its rheostat 10.
- 65 When there is a sudden increase in the load taken from the boiler, the mill is speeded up suddenly under control of its automatic rheostat 10, but we have found that there is not sufficient coal in the mill at this instant to prevent a sudden 70 decrease in the suction drop thru the mill, and, therefore, a period exists when the mill would rumble extensively unless provision is made to get additional coal into the mill. That is to say, the rapid increase in air flow due to speeding up the exhauster motor through means of the combustion control mechanism J would tend to clear the mill quickly, and although the feeder motor is also accelerated to its maximum speed position as represented by the position of the rheostat 10, the suction will still be too low for a period of time so that it is desirable to accelerate the feed beyond that which would ordinarily be used for regulation. This situation is reflected at the exhauster inlet and, therefore, we propose to connect to the suction pipe 44, a second suction relay device 55, similar to the suction relay device 46. The suction relay device 55 is adapted to operate a mercoid switch 56 which, in turn, controls a fast magnetic relay 57. The fast relay 57 cuts in or cuts out an additional field resistance 58 associated with the rheostat 10 as indicated in the wiring diagram. The contacts 59 of the magnetic relay 57 are normally closed and when the suction to the suction relay 55 drops to a predetermined value, it is operated to move the mercoid switch 56 to a position in which a mercury contact is made at 60 and this, in turn, causes the magnetic relay 57 to be energized, thus opening the contacts 59. When the contacts 59 are opened the extra resistance 58 is included in the field circuit and the feeder motor speeds up to its maximum speed. As soon as the suction builds up to the proper value, the fast suction relay 55 resets and deenergizes the magnetic relay 57, permitting the combustion control mechanism H and J to again act as the controlling medium in its usual fashion.

relays in addition to the speed changes effected by the combustion control mechanism referred to.

The following is an example as to the approximate values at which the suction relays would be set if it is desired to hold a suction of 4.25" water gage at the exhaust inlet. The fast suction relay 55 would be set so that the contacts 59 would open at 4.15" suction and close at 4.00" suction. The slow suction relay 61 would be set 10 so that the contacts 64 would open at 4.35" suction and close at 4.50" suction. The stop suction relay 46 would be set so that the contacts 54 would open at 4.75" suction and close at 4.60" suction. With such settings approximate constant suction would be maintained at the 15 exhaust inlet.

While the diagram illustrates the use of a D. C. feeder motor with regulation of the feed by adjustment of the shunt field, it is to be understood that we contemplate connecting the suction relays in a manner to control two motors or a two speed motor as would be the case in A. C. circuits. Also in some instances we may utilize a jumper connection in place of the extra 20 resistance 58.

From the foregoing it will be seen that we have provided a very simple, and effective control system for boiler installations which operates to automatically control the feeder, mill, 30 and exhaust speeds to ensure proper firing under normal changes in load conditions and also operates to additionally automatically control the feeder speed to ensure proper coal conditions in the mill when there is a sudden change in load.

35 While we have illustrated our invention in connection with a directly fired boiler installation, it is to be understood that the advantages to be derived therefrom may also be obtained in indirectly fired installations. Also in some installations very satisfactory results may be obtained by using the stop suction relay device 46 without the suction relay devices 55 and 61.

We claim:—

1. In combination of a boiler and furnace and means for firing the furnace, said firing means including a pulverizer, a fuel bin, a feeder for feeding fuel from the bin to the pulverizer, an exhaust fan for feeding pulverized fuel from the pulverizer to the furnace, automatic means 50 for simultaneously controlling the speed of the feeder, the pulverizer and the exhaust fan responsive to variations of the steam pressure in the boiler, and automatic means independent of said first mentioned means for further controlling the speed of the feeder responsive to variations of the suction of the exhaust fan.

2. A pulverized coal burning installation including a boiler, a furnace, a mill for pulverizing the coal, a feeder for delivering coal to the mill, 60 an exhaust for drawing pulverized coal from the mill for delivery to the furnace, automatic means responsive to variations of the steam pressure of the boiler for simultaneously controlling the speed of the mill, the feeder and the exhaust and automatic means independent of said first 65 mentioned means for further controlling the speed of the feeder responsive to variations of the suction of the exhaust.

3. In a pulverized coal burning installation, the combination of a boiler; a furnace; a coal pulverizer, a coal feeder, and an exhaust fan, each having an electric driving motor; a rheostat controlling the speed of each motor; automatic means responsive to variations of the steam pressure 70 of the boiler for simultaneously operating said motor including a magnetic switch in the feeder

rheostats, manually operating means for adjusting said rheostats, and automatic means responsive to variations of the suction of the exhaust fan for controlling the speed of the feeder motor independently of the setting of its rheostat.

80

4. A pulverized coal burning installation including a boiler, a furnace, a mill for pulverizing the coal, a feeder for delivering coal to the mill, an exhaust for drawing pulverized coal from the mill and delivering it to the furnace, automatic means for simultaneously controlling the speed of the mill, feeder, and fan responsive to variations of the steam pressure of the boiler, and automatic means independent of said first mentioned means for further controlling the speed of the feeder responsive to variations of the suction at the suction side of the fan.

85

5. In a boiler installation, the furnace of which is fired by direct delivery of fuel thereinto from a mill, the combination of a motor driven mill, a motor driven feeder for delivering fuel to the mill, a motor driven exhaust for drawing fuel from the mill and delivering it into the furnace, automatic means for simultaneously controlling the speed of said motors including a speed controller for each motor, steam pressure actuated mechanism for operating said controllers, means for delivering actuating steam to said mechanism from the boiler, and other automatic means independent of the first means for further controlling the speed of the feeder motor including means responsive to variations of the suction of the exhaust for controlling the speed of the feeder motor beyond the control afforded by the first mentioned control means.

95

6. In a boiler installation, the furnace of which is fired by direct delivery of fuel thereinto from a mill, the combination of a motor driven mill, a motor driven feeder for delivering fuel to the mill, a motor driven exhaust for drawing fuel from the mill and delivering it into the furnace, automatic means for simultaneously controlling the speed of said motors including a rheostat controlling each motor, means for operating the rheostats, steam pressure actuated mechanism for 100 actuating said operating means, means for delivering actuating steam to said mechanism from the boiler, and other automatic means independent of said first mentioned means for further controlling the speed of the feeder motor including means responsive to variations of the suction of the exhaust for controlling the speed of the feeder motor beyond the control afforded by the first mentioned control means.

110

6. In a boiler installation, the furnace of which is fired by direct delivery of fuel thereinto from a mill, the combination of a motor driven mill, a motor driven feeder for delivering fuel to the mill, a motor driven exhaust for drawing fuel from the mill and delivering it into the furnace, automatic means for simultaneously controlling the speed of said motors including a rheostat controlling each motor, means for operating the rheostats, steam pressure actuated mechanism for 115 actuating said operating means, means for delivering actuating steam to said mechanism from the boiler, and other automatic means independent of said first mentioned means for further controlling the speed of the feeder motor including a switch for said feeder motor, a suction relay adapted to open and close said switch, and a suction line leading from the suction side of the exhaust for said suction relay.

115

7. A pulverized coal burning installation including a boiler, a furnace, a mill for pulverizing the coal, a feeder for delivering coal to the mill, an exhaust for drawing pulverized coal from the mill for delivery to the furnace, an electric driving motor for the mill, an electric driving motor for the feeder, an electric driving motor for the exhaust, a rheostat in the mill motor circuit for controlling the speed of the mill motor, a rheostat in the feeder motor circuit for controlling the speed of the feeder motor, a rheostat in the exhaust motor circuit for controlling the speed of the exhaust motor, automatic means responsive to variations of the steam pressure of the boiler for simultaneously controlling the speed of said mill, feeder, and exhaust motors through the medium of their rheostats, and automatic means independent of said first means responsive to variations of the suction of the exhaust for further controlling the operation of the feeder for 120 the medium of their rheostats, and automatic means independent of said first means responsive to variations of the suction of the exhaust for further controlling the operation of the feeder for 125 the medium of their rheostats, and automatic means independent of said first means responsive to variations of the suction of the exhaust for further controlling the operation of the feeder for 130 the medium of their rheostats, and automatic means independent of said first means responsive to variations of the suction of the exhaust for further controlling the operation of the feeder for 135 the medium of their rheostats, and automatic means independent of said first means responsive to variations of the suction of the exhaust for further controlling the operation of the feeder for 140 the medium of their rheostats, and automatic means independent of said first means responsive to variations of the suction of the exhaust for further controlling the operation of the feeder for 145 the medium of their rheostats, and automatic means independent of said first means responsive to variations of the suction of the exhaust for further controlling the operation of the feeder for 150 the medium of their rheostats.

motor circuit adapted to stop the motor, and a switch for controlling said magnetic switch to stop and start the feeder motor.

8. A pulverized coal burning installation including a boiler, a furnace, a mill for pulverizing the coal, a feeder for delivering coal to the mill, an exhauster for drawing pulverized coal from the mill for delivery to the furnace, an electric driving motor for the mill, an electric driving motor for the feeder, an electric driving motor for the exhauster, a rheostat in the mill motor circuit for controlling the speed of the mill motor, a rheostat in the feeder motor circuit for controlling the speed of the feeder motor, a rheostat in the exhauster motor circuit for controlling the speed of the exhauster motor, automatic means responsive to variations of the steam pressure of the boiler for simultaneously controlling the speed of said mill, feeder, and exhauster motors through the medium of their rheostats, and automatic means independent of said first mentioned automatic means responsive to variations of the suction of the exhauster for further controlling the operation of the feeder motor including a magnetic switch in the feeder motor circuit adapted to stop the motor, a magnetic switch in the field circuit of the feeder motor adapted to control the speed of the feeder motor by control of the field, a switch for controlling the first mentioned magnetic switch to stop and start the feeder motor, and a switch for controlling the second mentioned magnetic switch to vary the speed of the feeder motor.

9. A pulverized coal burning installation including a boiler, a furnace, a mill for pulverizing the coal, a feeder for delivering coal to the mill, an exhauster for drawing pulverized coal from the mill for delivery to the furnace, an electric driving motor for the mill, an electric driving motor for the feeder, an electric driving motor for the exhauster, a rheostat in the mill motor circuit for controlling the speed of the mill motor, a rheostat in the feeder motor circuit for controlling the speed of the feeder motor, a rheostat in the exhauster motor circuit for controlling the speed of the exhauster motor, automatic means responsive to variations of the steam pressure of the boiler for simultaneously controlling the speed of said mill, feeder, and exhauster motors through the medium of their rheostats, and automatic means independent of said first mentioned automatic means responsive to variations of the suction of the exhauster for further controlling the operation of the feeder motor including a magnetic switch in the field circuit of the feeder motor adapted to cause the feeder motor to slow down by control of the field thereof, and a switch for controlling said magnetic switch to slow down the feeder motor.
10. A pulverized coal burning installation including a boiler, a furnace, a mill for pulverizing the coal, a feeder for delivering coal to the mill, an exhauster for drawing pulverized coal from the mill for delivery to the furnace, an electric driving motor for the mill, an electric driving motor for the feeder, an electric driving motor for the exhauster, a rheostat in the mill motor circuit for controlling the speed of the mill motor, a rheostat in the feeder motor circuit for controlling the speed of the feeder motor, a rheostat in the exhauster motor circuit for controlling the speed of the exhauster motor, automatic means responsive to variations of the steam pressure of the boiler for simultaneously controlling the speed of said mill, feeder, and exhauster motors through the medium of their rheostats, and automatic means independent of said first mentioned automatic means responsive to variations of the suction of the exhauster for further controlling the operation of the feeder motor including a magnetic switch in the field circuit of the feeder motor adapted to cause the feeder motor to slow down by control of the field thereof, and a switch for controlling said magnetic switch to slow down the feeder motor.
11. A pulverized coal burning installation including a boiler, a furnace, a mill for pulverizing the coal, a feeder for delivering coal to the mill, an exhauster for drawing pulverized coal from the mill for delivery to the furnace, driving means for the mill, driving means for the feeder, driving means for the exhauster, automatic means for simultaneously controlling the speeds of the said driving means responsive to variations of the steam pressure of the boiler, an automatic means independent of said first mentioned automatic means for further controlling the speed of the driving means for the feeder including a plurality of devices responsive to variations of the suction of the exhauster each adapted to be set to operate at predetermined values of suction, means associated with one of said devices adapted to stop the feeder driving means when the suction reaches a predetermined value, means associated with another of said devices adapted to reduce the speed of the feeder driving means when the suction reaches a predetermined value lower than that at which said first device operates and means associated with another of said devices adapted to increase the speed of the feeder driving means when the suction drops to a value below that at which the other devices operate.
